UNITED STATES PATENT OFFICE.

SAMUEL FIERBAUGH, OF HUNTINGTON, WEST VIRGINIA, ASSIGNOR OF
ONE-HALF TO J. C. MILLER, OF SAME PLACE.

TRACK-GAGE.

SPECIFICATION forming part of Letters Patent No. 662,925, dated December 4, 1900.

Application filed March 12, 1900. Serial No. 8,423. (No model.)

To all whom it may concern.

Be it known that I, SAMUEL FIERBAUGH, a citizen of the United States, residing at Huntington, county of Cabell, and State of West Virginia, have invented certain new and useful Improvements in Track-Gages, of which the following is a full, clear, and exact description, reference being had therein to the accompanying drawings, in which—

10 Figure 1 is a side elevation of the gage as used on a straight track; Fig. 2, a similar view of the gage as used on a curved track, the left-hand rail being the outer or raised rail; Fig. 3, an enlarged plan view, the lifting-bail being removed; Fig. 4, an enlarged transverse sectional view on line 4-4 of Fig. 2.

The object of the invention is to provide a track-gage for use in the construction and maintenance of railway-tracks which because of its simplicity of construction and ease of operation will enable a workman with no knowledge of engineering to maintain the rails parallel at the proper distance apart and to give the road-bed the proper transverse 25 inclination on curves and to locate the center of the track.

The invention consists in providing a main section of a length equal to the width or gage of the track, its outer lower corners being cut out to form recesses to receive the rails, as in the ordinary track-gage, and a supplemental or movable section, preferably at the center of the main section, said supplemental movable section being pivoted at one end and normally projected upward at its other end, a suitable level being carried by this central section and suitable scale devices being employed, whereby the desired transverse inclination of the track can be determined. Suitable adjusting devices are carried by the main section and engage the free end of the pivoted section to regulate the upward movement thereof.

Referring to the various parts by numerals, 1 designates the main section of the track-gage, which may be of any suitable material and has its lower outer corners cut out to form recesses to receive the rails, as in ordinary track-gages. At the center of the upper edge of this main section is formed a recess whose end walls incline inward and

downward, and closely fitting this recess is a supplemental section 2, whose upper surface when the gage is used as a straight-track gage is flush with the upper surface of the main section. Rigidly secured to the right-hand end of this supplemental section and to the adjacent upper surface of the main section is a flat spring 3, which connects the two sections and forms a spring hinge or pivot which normally maintains the free left-hand end of the movable section projected upward away from the main section of the gage. The free end of the supplemental section is provided with a plate 4, one end of which projects out over the adjacent upper surface of the main section, this projecting end being formed with a central notch or recess 5, within which fits a vertical screw 6, carried by the main section of the gage, said screw forming a guide and preventing any lateral movement of the movable section. On this screw is a gage-nut 7, which may be screwed down on top of the recessed outward-projecting end of the plate 4 to hold the supplemental section in position to adapt the gage for straight-track work. On one side of the pivoted supplemental section, near the free end thereof, is an elevation indicator or scale 8, and adjacent this scale, but secured to the main section of the gage, is a rigid pointer 9, whose upper end is in line with the upper scale-mark when the gage is adapted for straight-track work. This pointer fits closely against the side of the movable section and forms a guide and a lateral brace therefor. Secured to the side of the main section of the gage, on the opposite side thereof from the pointer 9, is a spring-latch 10, formed with a series of transverse notches 11, which are adapted to engage the adjacent edge of the plate 4, carried by section 2, and prevent the upward movement of the free end of said section 2 when it is released from the gage-nut 7, and also forming a guide for the movable section. In the center of the movable section, in the upper surface thereof, is a spirit-level 12, and directly below the level in the center of the lower surface of the rigid main section is a depending pin 13, by means of which the transverse center of the track may be accurately located.

In operation when the gage is used on straight-track work the gage-nut 7 is screwed down tight to hold the movable section down in the recess in the main section, as shown in Fig. 1, and the gage is then used in the ordinary way. When it is desired to use the device on curved sections of track, where it is necessary to give the road-bed a transverse inclination, the gage-nut is unscrewed to approximately the desired point on its screw, and then the latch 10 is released from plate 4 to permit the free end of the movable section to rise, the spring 3 lifting the free end of the section 2 until the plate 4 contacts with the under side of the gage-nut. Then by means of this gage-nut the free end of the movable section 2 may be nicely adjusted—that is, depressed or permitted to rise until the scale on the side of this section indicates the inclination it is desired to give the road-bed. The outer rail of the curved section of the track is now placed at such a height that when the gage-bar is placed on the rails the upper surface of the movable section will be level. The track will then have the desired transverse inclination. A handle or bail 14 is secured to the upper surface of the gage to enable it to be readily handled and to protect the latch 10 and the screw 6.

It will be noted that the catch 10 takes the strain of the spring off the gage-nut 7 and that said nut may therefore be quickly raised to the desired point on the screw 6 whenever desired without loss of time and with but slight effort, and that when it is desired to depress the movable section the same may be pushed bodily downward by the hands and then held in its depressed position by the catch 10. The gage-nut can then be quickly and easily screwed down to accurately adjust the movable section or to clamp it in its recess in the main section. It will also be noted that a feature which contributes to the utility of the device lies in mounting the level-carrying section in a recess in the main section shaped similarly to itself, so that said level-carrying section may be depressed into said recess and be substantially flush with the surfaces thereof and be braced and supported in such a way as to constitute, in effect, a part of the main bar and be thereby protected from injury in the rough handling devices of this sort usually receive. It will also be observed that by thus employing a level-carrying section normally pressed upward at its free end a much more positive and nicer adjustment can be obtained than

could be obtained were this section mounted so as to normally rest on the main bar; also, that the screw and spring device enables the adjustment to be made very quickly, as the central section may be held down by the hand or by latch 10 while the screw-nut is run up or down to get the approximate adjustment.

It will be further obvious that, if desired, the notches in the spring-catch 10 may correspond in number to the divisions on the scale-plate of the elevation-indicator, so that the catch may be employed to hold the level-carrying section at the desired point, in which case the nut will serve more as a safety device to prevent the level-carrying section springing up in case the catch should be accidentally thrown out of engagement with it.

Having thus fully described my invention, what I claim, and desire to secure by Letters Patent, is—

1. A track-gage comprised of a main section, a movable section carrying a level and pivoted at one end to the main section, means for normally elevating the free end of the level-carrying section, a movable latch device consisting of a part carried by the main section and having a series of notches adapted to engage and prevent the free end of the level-carrying section springing upward, a screw device connecting the free end of the level-carrying section to the main section and adapted to restrict its upward movement, and an elevation-indicator.

2. In a track-gage, the combination of a main section, a level-carrying section pivoted thereto, a spring normally pressing the free end of said section upward, a spring-catch carried by one section and adapted to normally engage the other section, a screw device carried by the main section and engaging the movable section, and an elevation-indicator.

3. In a track-gage, the combination of a main section, a supplemental section pivoted at one of its ends to the main section and having its free end normally pressed upward, a vertical screw carried by the main section, a notched plate carried by the movable section and having one end project over the main section, said projecting end engaging the screw, a nut carried by the screw, and an elevation-indicator, substantially as described and for the purpose set forth.

SAMUEL FIERBAUGH.
